UNITED STATES PATENT OFFICE.

SAMUEL E. CLARKSON, OF JOHNSTOWN, PENNSYLVANIA, ASSIGNOR TO
THE LORAIN STEEL COMPANY, OF PENNSYLVANIA.

MOTOR SUSPENSION.

SPECIFICATION forming part of Letters Patent No. 644,197, dated February 27, 1900.

Application filed August 22, 1899. Serial No. 728,072. (No model.)

To all whom it may concern:

Be it known that I, SAMUEL E. CLARKSON, of Johnstown, in the county of Cambria and State of Pennsylvania, have invented a new and useful Improvement in Motor Suspensions, of which the following is a full, clear, and exact description, reference being had to the accompanying drawings, which form a part of this specification.

My invention relates to certain new and useful improvements in motor suspensions for electric vehicles, and is designed to provide a suspension having the desired degree of flexibility and elasticity, in which the number of parts, including the cushioning-springs, is reduced to a minimum and in which the motors, sleeved to the vehicle-axles at one end in the usual manner, are rendered mutually supporting at their nose ends, connections to the vehicle-body and to the truck-frame being obviated.

With these objects in view the invention consists in the novel construction and combination of parts, all as hereinafter described, and pointed out in the appended claims, reference being had to the accompanying drawings, in which—

Figure 1 is a plan view illustrating the application of my invention; Fig. 2, a side view of the same; Fig. 3, a detail view of one of the spring-cushions, and Fig. 4 a partial plan illustrating a modification.

In the drawings the letters A A' designate the two motors, which are sleeved, respectively, upon the two axles B B' in the usual manner.

C designates a rigid bar—in the present instance an I-beam—which rests at its ends upon the tops of the motor-casings, as shown. Seats c, having dovetailed walls, may be cast in the motor-casings to receive the end portions of the said bars, said seats being of sufficient length to permit endwise movement of the bars therein and closed at their outer ends to guard against undue endwise movement.

The nose end of each motor-casing is formed with a horizontally-projecting lug D, cast integrally therewith or otherwise provided.

Loosely supported on each of these lugs is a

of a stiff helical spring F. The upper end of said spring seats against a cap-plate G, which bears upon the under side of the I-beam. The spring-seat E is supported from the I-beam by means of a U-bolt H, whose closed end embraces said beam and which is secured in the spring-seat by nuts h. This U-bolt embraces the spring F. K is a second bolt, whose legs are passed up through the lug D inside the spring and through the cap-plate G, at the upper side of which they are secured by nuts h. Arranged in this manner it will be readily seen that the weight of the motors is first carried by the springs G through the bolts K and cap-plates G and through said spring, the spring-seats E, and the U-bolts H is transmitted to the I-beams, thereby relieving the axles to a very large extent of the dead-weight of the motors and the consequent hammer and jar thereof in running. The upward thrust of the motors, due to torque, is taken by the springs through the spring-seats E, while the downthrust is similarly taken through the cap-plates G. The one set of springs is thereby made to form an effective cushion for the thrust of the motors in both vertical directions.

In Fig. 4 I have shown the suspension as applied to motors having nose-lugs P. In this case I secure to said lugs a transverse bar P', upon which the lower spring-seats are supported. Instead of the seats in the top of the motor-casings for the end portions of the I-beam I secure the latter loosely thereto by means of hooks R, which engage the base-flanges of said beam. I also provide suitable stops S to guard against undue endwise movement of the I-beams.

I do not wish to limit myself to the particular construction and arrangement I have herein shown and described, as the same may be varied without departing from the spirit and scope of my invention as pointed out in the appended claims.

Having thus described my invention, what I claim, and desire to protect by Letters Patent, is—

1. The combination with two motors, each of which is sleeved to a vehicle-axle, of a connecting-bar resting at its end portions upon the motor-casings and secured loosely there-

to, springs interposed between said bar and the nose or free ends of the motors, and means whereby the vertical thrust of the motors in either direction effects a compression of the 5 said springs.

2. The combination with two motors, each of which is sleeved to a vehicle-axle, of a longitudinal connecting-bar loosely seated at its ends upon the motor-casings, springs interposed between the said bar and the nose or free ends of the motors, and means whereby the vertical thrust of the motors in opposite directions is applied to opposite ends of the same spring, to effect compression thereof.

15 3. The combination with two motors, each of which is sleeved to a vehicle-axle, of a longitudinal connecting-bar seated upon the tops of the motor-casings for limited endwise movement, springs seated between the under side 20 of the said bar and projections at the nose or free ends of the motors, and means whereby thrust of the motors in both vertical directions effects compression of the same springs.

4. The combination with two motors, each 25 of which is sleeved to a vehicle-axle, and the connecting-bar seated thereon, of a single spring interposed between the said bar and the nose or free end of each motor, and means whereby said spring is compressed by vertical thrust of the motor in either direction.

5. The combination with the two motors, each sleeved at one end to one of the driving-axles, and a connecting-bar seated on the motors, of top-bearing spring-caps carried by 30 the motors at their free ends, bottom-bearing spring-caps, suspended from the said bar to be engaged by the motors upon upward move-

ment thereof and springs seated between the said caps and compressed from one end by downward movement of the motors and from 40 the other end by upward movement of the same.

6. In a motor suspension, the combination with a motor sleeved at one end to one of the driving-axles, of a supporting-spring for the 45 free or nose portion of the motor, and means whereby downward movement of the motor about the axle effects a compression of said spring from one end and upward movement of the same effects a compression thereof from 50 the opposite end.

7. The combination with the sleeved motors having spring-supports at their free or nose ends, and a beam or bar resting upon and loosely connecting said motors, of the spring-seats E, the U-bolts which suspend said seats from the said beam or bar, the cap-plates G, the bolts which carry the same from the said supports, and the coil-springs interposed between seats and plates, one of said bolts passing through each of the said springs, and the other bolt embracing the same.

8. The combination with two motors, each of which is sleeved to a vehicle-axle, of an elastic connection for the motors supported by 65 bearings on the tops of the motor frames or casings and also connected with the free or nose portions of the motors.

In testimony whereof I have affixed my signature in presence of two witnesses.

S. E. CLARKSON.
